[57] CLAIM

The ornamental design for a seat, as shown and described.

DESCRIPTION

FIG. 1 is a front perspective view of a seat showing my design in the form of an armchair; and,

FIG. 2 is a front elevational view thereof;

FIG. 3 is a front perspective view of a seat showing my design in the form of a sofa; and,

FIG. 4 is a front elevational view thereof.

FIG. 5 is an elevational view showing one of the two identical ends of the seat.

The rear of the seat is conventional in appearance.

FIG. 1

FIG. 2

FIG. 3

FIG. 4

FIG. 5
